DESIGN FOR A COMBINATION ASH TRAY AND LIGHT

George David Amato, Astoria, Oreg.

Application October 30, 1946, Serial No. 134,378

Term of patent 14 years

(Cl. D48—20)

To all whom it may concern:

Be it known that I, George David Amato, a citizen of the United States of America, residing at Astoria, in the county of Clatsop and State of Oregon, have invented a new, original, and ornamental Design for a Combination Ash Tray and Light, of which the following is a specification, reference being had to the accompanying drawing, forming a part thereof.

In the drawing:

Figure 1 is a perspective view of a combination ash tray and light embodying my invention.

Figure 2 is a top plan view on a reduced scale of the article shown in Figure 1 with the ash tray member removed.

I claim:

The ornamental design for a combination ash tray and light, as shown.

GEORGE DAVID AMATO.
